CARBURETOR

Albert H. Winkler, South Bend, Ind., assignor to
Bendix Aviation Corporation, South Bend,
Ind., a corporation of Delaware

Application May 16, 1941, Serial No. 393,692

12 Claims. (Cl. 123—127)

This invention relates generally to carburetors for internal combustion engines and more particularly to throttle valve control means for multiple stage carburetor systems.

Multiple stage carburetor systems for internal combustion engines such as are commonly used in automotive vehicles or the like may comprise either a plurality of independent carburetors or an integral carburetor having a plurality of induction passages. In either arrangement, there are a plurality of induction passages connected with a common intake manifold or complementary manifolds, throttle valves for the respective passages and means for controlling said valves whereby the respective stages of the carburetor system are brought into operation progressively.

In carburetor systems of this character difficulty has been encountered in properly controlling the fuel-to-air ratio of the fuel mixture during the starting and warming-up period of engine operation particularly when the temperature of the engine is low.

When the engine is cold, it requires a very rich mixture for starting and a somewhat leaner mixture during the warming-up period, although during said warming-up period a richer mixture is normally required than when the engine is operating at its normal temperature. During said warming-up period of engine operation it is particularly desirable that the velocity of the air in the induction passages of the carburetor system be as great as possible in order to pick up sufficient fuel to provide a suitable mixture of combustible proportions and to maintain the fuel in the air stream and obtain the proper degree of equal distribution of the fuel mixture to the various cylinders of the engine.

Such desired high velocities of air will be present in the primary induction passage of the carburetor system as long as all or substantially all of the air entering the induction system of the engine passes through said primary induction passage. However, as it is often difficult for the operator of the automobile to determine accurately how far the accelerator pedal may be depressed without opening the supplementary throttle valve, said valve may be inadvertently opened during the starting or warming up period of engine operation and a part of the air to the engine induction system will enter through the supplementary induction passage or passages and the velocity of said entering air will be greatly reduced.

The expedient of providing a conventional choke valve in each of the induction passages and

controlling same by any of the usual manual or automatic means increases the cost of the carburetor system and does not solve the problem of controlling the fuel-to-air ratio under the above mentioned conditions of engine operation and it is, therefore, an important object of the invention to provide relatively inexpensive means for overcoming said difficulties in controlling the fuel-to-air ratio in a multiple stage carburetor system during the starting and warming-up period of engine operation.

Another object of the invention is to provide, in a multiple stage induction system, means for rendering the supplementary part of the induction system inoperative when the engine is operated at subnormal temperatures.

Still another object of the invention is to provide, in a multiple stage carburetor system having a plurality of induction passages with valves controlling the fluid flow therethrough, temperature responsive means for locking at least one of said valves in the closed position when the engine is operated at subnormal temperatures.

A further object of the invention is to provide a device of this character wherein the locking means is responsive to engine temperature.

A still further object of the invention is to provide a device of this character including means to permit full opening of the primary throttle valve while the supplemental supply is rendered inoperative when the engine temperature is subnormal.

In one of the types of multiple stage carburetors an auxiliary unbalanced throttle valve, operable by the differential of pressures on opposite sides thereof, is provided for the supplementary mixture passage or passages and it is another object of the invention to provide temperature responsive means for latching such unbalanced valves in the closed or substantially closed position when the temperature of the engine is below normal.

The characteristics and advantages of the invention are further sufficiently referred to in connection with the following detailed description of the accompanying drawing which represents certain preferred embodiments. After considering these examples, skilled persons will understand that many variations may be made without departing from the principles disclosed; and I contemplate the employment of any structures, arrangements or modes of operation that are properly within the scope of the appended claims.

In the drawing:

Figure 1 is a fragmentary elevational view of an integral combustion engine provided with a mul-

multiple stage fuel induction system employing the invention; and

Figure 2 is a similar view disclosing a modified form of the invention.

While the present invention is shown and described embodied in a multiple stage carburetor system having a plurality of independent carburetors it may be embodied in an integral carburetor having a plurality of induction passages. Further, the present invention is illustrated and described as embodied in a carburetor system of this character having one primary and one auxiliary or supplemental induction passage, although it may be embodied in such a system having a plurality of both primary and supplemental induction passages or a single passage for one stage and a plurality of passages for another stage or stages. It may also be embodied in a system of this character wherein the engine has a dual or multiple type of intake manifold, each part of which has connected therewith corresponding primary and/or supplementary induction passages.

Throughout the drawing, similar reference characters represent similar parts, although where such parts are modified in structure and operation, they are given a further differing reference character, and in the specification and claims reference to the engine as being "cold," or its temperatures as being "normal," "subnormal" or "low" relates to normal operating temperatures thereof.

Referring now to Figure 1, reference numeral 10 indicates an engine generally and 12 indicates the intake manifold thereof having attached thereto a primary carburetor P and a secondary or supplementary carburetor S. Both carburetors comprise an air horn section 14, a body section 16 and a throttle body section 18 and each carburetor has an induction passage including an air entrance 20, venturis (not shown) and mixture chamber 22, a fuel chamber 24, fuel nozzle 26, and simple idling system 28. The primary carburetor P is also provided with the usual acceleration pump and economizer system indicated at 30 and 32 respectively. However, if desired, the secondary or supplemental carburetor S may also be provided with an acceleration pump and economizer system. Said primary carburetor P is further provided with the usual unbalanced choke valve 34 on a shaft 36 which may be manually or automatically operated in any known manner. The shaft 36 is provided with a lever 42 connected to a fast idle cam 44 by a rod 46, said cam being engageable with a screw 48 in one arm of a throttle lever 50 secured to a throttle shaft 52 carrying the primary throttle valve 54. However, any other suitable fast idling mechanism may be provided. Throttle shaft 53 of the secondary carburetor carries a throttle valve 56 and has a lever 58 secured to one end thereof. A spring 59, attached to lever 58 is provided to yieldingly close throttle valve 56.

Means for manually operating both throttle valves includes a bell crank pivoted at 60. One arm 62 of the bell crank is connected with the primary throttle lever 50 by means of a rod 64 and the other arm 66 of the bell crank has an overriding connection with one end of a lever 68 which is pivoted at 70, said connection including a rod 72 slidably received in a collar 74 pivoted on the lever 68. A member 76 fixed to rod 72 in spaced relation to collar 74 is adapted to engage said collar upon opening movement of the throttle valve actuating mechanism to nor-

mally effect opening movement of the secondary throttle valve 56 after the primary throttle valve 54 has been opened a predetermined amount. The other end of lever 68 is connected with throttle lever 58 by means of a rod 80 which is slidably received in a collar 82 pivotally attached to the lever 58. A member 84 is secured to rod 80 adjacent its free end and is spaced from said collar 82, said rod 80 having a spring 86 thereon which reacts between the member 84 and collar 82, said spring 86 being of such character as to normally overcome the valve closing pressure of spring 59 when the throttle valve actuating mechanism is actuated in the opening direction and the lost motion between collar 74 and member 76 has been exhausted. The throttle valves are actuated by the usual acceleration pedal (not shown) connected with lever 66 by a rod 67.

Temperature responsive means for locking the secondary throttle valve in its closed or substantially closed position when the engine temperature is below normal comprises a lever 90, pivoted at 92 to a convenient fixed member and having a lug 94 adjacent its free end adapted to engage a finger 96 adjacent the free end of lever 58. A bimetallic thermostatic element 98 is attached at one end to a pin 100 secured in lever 90 and at the other end to a lug 102 formed integral with or attached to some convenient part of the engine to be thereby responsive to variations in engine temperature.

The operation of the above described mechanism is as follows:

When the engine is not in operation both throttle valves are normally closed and when the engine temperature is below that of normal operation the lever 90 is so positioned by the thermostatic element 98 that lug 94 is beneath finger 96 of lever 58, thereby preventing opening of throttle valve 56 by the throttle valve operating mechanism and rendering the supplemental source of fuel mixture inoperative. Therefore, during cold starting and the warming-up period the engine is supplied with a fuel mixture only from the primary carburetor. Throttle valve 54 may be opened in the usual manner by actuation of the acceleration pedal, and the usual choke valve 34 (or other mixture enrichment device) of the primary carburetor and the actuating mechanism therefor controls the richness of the mixture for starting and during the warming-up period of engine operation. It is apparent, therefore, that locking of the throttle valve 56 in the closed or substantially closed position makes unnecessary the use of a choke valve in the secondary carburetor and the normal functions of the fuel induction system during starting and warming-up of the engine are taken care of in the usual manner by the primary carburetor. As all of the air to the engine then passes through the primary induction passage when the engine is operated below normal temperature, the velocity of said air is much greater than it would be if some of it were also admitted through the secondary induction passage. Consequently, with high velocities of air in the primary induction passage sufficient fuel is picked up by said air and sustained thereby to provide the engine with a suitable mixture of combustible proportions for all normal starting and warming-up requirements thereof.

It should be noted, however, that the requirements of certain engines may make it desirable to set the supplementary throttle valve 56 in a slightly open position to provide a suitable idling

mixture and this may be done without materially reducing the velocity of air in the induction system during starting and warming-up periods of engine operation.

When the throttle valve 56 is locked in the closed or substantially closed position, the primary throttle valve 54 may be fully opened, if the operator so desires, and said opening of valve 54 will not be prevented by said locking of the secondary throttle valve, due to the override between rod 72 and lever 68 and the yielding of spring 86 of the overriding connection between rod 80 and lever 58. The amount of lost motion of said overriding connections corresponds to that movement of the operating mechanism for fully opening the primary throttle valve.

After starting the engine and as same warms up, the thermostatic element 98 moves lever 90 to the right, as shown in Figure 1, and when the engine temperature reaches normal, lever 90 is moved out of the path of finger 96, thereby permitting normal opening of throttle valve 56 by the valve actuating mechanism.

During the cooling off period of the engine, the throttle valve 56 is normally closed and the thermostatic element 98 moves lever 90 into a position whereat said valve 56 is locked against opening while the engine temperature is subnormal.

A modification of the invention is shown in Figure 2, wherein the primary throttle valve shaft 52 is provided with a lever 110, said lever having an extension 112, adjacent the free end of which is pivotally connected a rod 114, the other end of said rod being slidably received in a collar 116 pivoted to a secondary throttle lever 118 secured to one end of shaft 53. A flange 120 is secured to rod 114 in spaced relation to the collar 116 against which said flange is adapted to abut upon a predetermined opening movement of the valve opening mechanism and further valve opening movement of said mechanism is adapted to effect opening of the secondary throttle valve 56.

A riser 123 is interposed between the secondary carburetor S and the intake manifold 12 and is provided with a passage 124 which forms a continuation of the induction passage of said carburetor S. The riser has a shaft 126 on which is mounted an unbalanced auxiliary throttle valve 128 operable by air flow through passage 124 and closed by a weight 130 attached to one end of shaft 126. However, a spring or other suitable valve closing means may be substituted for said weight 130. Weight 130 has a projection or lug 132 adapted to be engaged, when valve 128 is closed, by a finger 134 of a lever 136 pivoted at 138 and actuated by a thermostatic element 140 having one end fixed to a stud 142 integral with the intake manifold 12. The thermostatic element is bent partially about the pivot 138 and connected to a pin 144 in lever 136. The thermostat is again positioned to respond to variations in the temperature of the engine.

It should be noted in connection with valve 128 that it may be desirable to permit slight opening thereof during the starting and warming-up period of engine operation to provide for the delivery of an idling mixture by the supplementary induction passage as well as by the primary passage. Such slight opening of said valve 128 may be provided by suitably spacing lug 132 and finger 134 of lever 136 when said valve is closed and the lever 136 is in the latching position.

It will be obvious from the foregoing description of the throttle valve actuating mechanism of the embodiment of Figure 2 that the throttle

valves may both be actuated in the normal manner, valve 56 opening later than valve 54.

However, the supplementary charge forming device is rendered inoperative when the engine temperature is subnormal by the thermostatic element 140 which controls lever 136 and moves same into and out of locking association with lug 132 of weight 130 according to whether the engine is below or at normal operating temperature.

When the engine temperature is subnormal the primary carburetor, which is a normal carburetor provided with a choke valve 34, fuel pump 30, economizer system 32, and fast idle (not shown) provides the engine with its fuel mixture in the usual manner. The fast idle may be of the type shown in Figure 1 or of any other suitable type. It should be noted, however, that the secondary carburetor may also be provided with an acceleration pump, economizer system and choke valve, if desired. Locking of valve 128 in the closed position when the engine temperature is subnormal prevents the secondary carburetor from delivering fuel mixture even though throttle valve 56 may be opened. At normal engine temperatures, with the latching mechanism disengaged, suction in the intake manifold will open valve 128 when throttle valve 56 is opened. The air flow auxiliary valve 128 is adapted to normally operate, when unlatched, in a manner similar to the auxiliary air flow valves disclosed in the co-pending application of Emil O. Wirth, for Charge forming devices, Serial No. 357,860, filed September 23, 1940, and the present invention may be used in connection with multiple stage charge forming systems such as are disclosed in said application, or it may be used in connection with carburetor systems such as disclosed in the co-pending application of Winkler and Gore, for Carburetors, Serial No. 384,274, filed March 20, 1941. It may also be used in multiple stage carburetor systems wherein the valves controlling the fuel mixtures are controlled by other types of manual or automatic means than those disclosed herein or in the above mentioned applications.

While the carburetors herein shown and described are of the downdraft type, the present invention may also be embodied in carburetors of any other suitable type such as, for example, the updraft or horizontal delivery type. It should also be noted that the multiple stage carburetor systems with which the present invention may be incorporated may comprise an integral carburetor with a plurality of induction passages as well as a plurality of independent carburetors as shown and described herein. Where said system comprises an integral carburetor, it may have a common air inlet for a plurality of induction passages with a single choke valve or it may have individual air inlets which choke valves therefor. The present invention may be embodied in any of the foregoing arrangements and where there are a plurality of supplemental induction passages it is preferable to provide thermostatic latching means of the present invention for each of the supplemental throttle valves therefor or the auxiliary valves thereof, although some engines may not require valve latching means for all of the supplementary passages. It should also be noted that any other suitable temperature responsive means may be employed to control the supplementary induction passage or passages.

However, it is not intended to limit the invention to the details shown or described, since said

invention provides certain new functions and it is intended to claim broadly the means for securing the same.

I claim:

1. In a multiple stage carburetor system for internal combustion engines having a plurality of induction passages controlled by throttle valves, means for actuating said valves in series, and temperature responsive means for rendering an induction passage inoperative when the engine temperature is low. 10

2. In a multiple stage carburetor system for an internal combustion engine having a plurality of induction passages controlled by throttle valves, means for progressively actuating said valves, and temperature responsive means adapted to prevent fluid flow through an induction passage when the engine temperature is subnormal. 15

3. The invention defined in claim 2, wherein, at least one throttle valve is fully openable at all times. 20

4. In a multiple stage carburetor system for internal combustion engines, said system having primary and supplemental induction passages for delivering primary and supplemental fuel mixtures, throttle valves for said induction passages, means for successively actuating said valves, and means responsive to engine temperature for preventing delivery of a supplemental mixture when the engine temperature is low. 25

5. In a multiple stage carburetor system for internal combustion engines, a plurality of induction passages, throttle valves controlling said passages, means for operating said valves in series, temperature responsive means for locking a throttle valve in a substantially closed position when the engine temperature is low, and means permitting at least partial opening of another throttle valve. 30

6. In a multiple stage carburetor system for internal combustion engines, a primary and a secondary induction passage, throttle valves for said passages, means for progressively opening said valves, and means responsive to engine temperature for locking the throttle valve of the secondary passage in a substantially closed position at subnormal operating temperatures of the engine. 35

7. The invention defined in claim 6, including means for permitting substantially full opening of the throttle valve for the primary induction passage when the secondary throttle valve is locked in said closed position. 40

8. In a multiple stage carburetor system for internal combustion engines, a primary and a secondary induction passage, a throttle valve for each passage, means for opening said valves whereby the secondary valve is opened later than the primary valve, temperature responsive means for locking the secondary valve in the closed position when the engine temperature is below normal and releasing said valve when said temperature is normal, and yielding means permitting full opening of the primary throttle valve when the secondary valve is locked. 45

9. In a multiple stage carburetor system for internal combustion engines, a plurality of induction passages and throttle valves therefor, means for actuating the throttle valves, an auxiliary valve in at least one of the induction passages operable by air flow through said induction passage, and temperature responsive means for locking said auxiliary valve in a substantially closed position when the engine temperature is below normal. 50

10. In a multiple stage carburetor system for internal combustion engines, a primary induction passage, a secondary induction passage, a throttle valve for each passage, means for progressively opening said throttle valves, a pressure responsive auxiliary valve in the secondary induction passage, means for urging said auxiliary valve toward closed position, and latching means responsive to engine temperature for latching the auxiliary valve in the closed position when the engine temperature is below normal. 55

11. In a multiple stage carburetor system for an internal combustion engine, a plurality of independent induction passages adapted to deliver fuel mixture into a common intake conduit, throttle valves for the respective passages each of which is normally closed, means for actuating the throttle valves, and temperature responsive means for rendering an induction passage inoperative when the engine temperature is low. 60

12. In an internal combustion engine having an intake passage, means forming a plurality of mixing conduits for supplying fuel to said passage, a manually operated throttle valve for one of said conduits, and a suction operated throttle valve for the other of said conduits, said last named throttle valve being so constructed and arranged as to be solely controlled by suction and temperature. 65

ALBERT H. WINKLER.
